UNITED STATES PATENT OFFICE.

GEORGE W. WOOLEY, OF ST. PAUL, MINNESOTA.

DESIGN FOR A BRACKET FOR PLANTERS.

SPECIFICATION forming part of Design No. 28,948, dated June 28, 1898.

Application filed January 10, 1898. Serial No. 666,251. Term of patent 7 years.

To all whom it may concern:

Be it known that I, GEORGE W. WOOLEY, residing in the city of St. Paul, county of Ramsey, State of Minnesota, have invented and produced a new and original Design for Brackets for Use in Planters or Similar Agricultural Machinery, of which the following is a specification, reference being had to the accompanying drawing, forming part thereof.

10 The single view in the said drawing shows in perspective a bracket designed in accordance with my invention.

By reference to the said drawing it will be seen that the leading and material features 15 of the design are, first, a plate-like body portion with downturned end flanges; second, a pair of parallel ears or lugs depending from each of said end flanges; third, a third pair

of parallel ears or lugs projecting horizontally, or approximately so, from one end of the body-plate, and, fourth, a post rising approximately from the center of said body-plate and terminating at its upper end in a bifurcated head or bulged prong.

Having described my invention, what I claim as new, and desire to secure by Letters Patent of the United States, is—

The design for a bracket for use in planters, &c., substantially as herein shown and described.

Dated at St. Paul, Minnesota, this 5th day of January, 1898.

GEORGE W. WOOLEY.

In presence of—

T. A. SHIRLEY,
JAS. MCLEAN.
